UNITED STATES PATENT OFFICE.

JAMES B. RYAN, OF NEW YORK, N. Y.

DESIGN FOR A PATTERN FOR WIRE FABRIC.

SPECIFICATION forming part of Design No. 27,838, dated November 9, 1897.

Application filed August 6, 1897. Serial No. 647,375. Term of patent 7 years.

To all whom it may concern:

Be it known that I, JAMES B. RYAN, a citizen of the United States, residing at the city of New York, county and State of New York, 5 have invented and produced a new and original Design for a Pattern for a Woven-Wire Fabric, of which the following is a specification.

My design for a pattern is illustrated in the 10 accompanying drawings referred to herein, and in which—

Figure 1 is a plan view of my design, and Fig. 2 is a cross-section of the same through the line 2-2 on Fig. 1.

15 The woven-wire fabric A is composed of longitudinal twisted and interwoven wires a,

forming lozenge-shaped loops a'. Through every fourth row of these loops the longitudinal duplex strands B are passed, two strands for each row of loops. They are interlaced 20 in the meshes of the fabric and so disposed as to form rows of elliptical-shaped loops b, each one of the loops b being within one of the lozenge-shaped loops a'.

What I claim is—

25 The design for a pattern for a woven-wire fabric herein described and set forth.

JAMES B. RYAN.
